EXPANSIBLE POLISHING WHEEL

William Krause, West Hartford, Conn., assignor
to Niles-Bement-Pond Company, Hartford,
Conn., a corporation of New Jersey

Application September 28, 1937, Serial No. 166,137

5 Claims. (Cl. 51—190)

This invention relates to polishing wheels and more particularly to an expansible wheel adapted to be axially compressed into a slightly radially expanded form to securely grip a flexible abrasive band surrounding the wheel.

An object of the present invention is to provide a polishing wheel that may be supported accurately and centrally in position upon its driving shaft so that the assembled wheel may 10 be rotated at high speeds without substantial vibration.

Another object of the invention is to provide an improved form of central support for the compressible and resilient material on which the 15 abrasive band is mounted, this support comprising a thin cylindrical shell of metal to the outer cylindrical surface of which is molded the rubber or other compressible material, there being end flanges on the driving shaft adapted to contact 20 with the end walls of the expansible material so that the outer diameter of this rubber may be slightly increased to firmly grip an endless band of abrasive-charged material mounted thereon.

One feature which is of importance is that the 25 flanges are provided with narrow cylindrical portions adapted to slidably contact with the internal surface of the metal shell or sleeve so that at all times the resilient and compressible material supporting the abrasive band is centrally supported upon its driving shaft.

And finally it is an object to provide axially disposed clamping means for drawing together the flanges so that the abrasive band may be firmly gripped upon the expansible center.

With the above and other objects in view, the 35 invention includes the features of construction and operation set forth in the following specification and illustrated in the accompanying drawing.

In the accompanying drawing annexed hereto 40 and forming a part of this specification, I have shown the invention embodied in an expansible polishing wheel of medium diameter and width, but it will be understood that the invention can be otherwise embodied and that the drawing is 45 not to be construed as defining or limiting the scope of the invention, the claims appended to this specification being relied upon for that purpose.

The figure of the drawing shows a sectional 50 view taken centrally through one form of the invention.

In the above-mentioned drawing there has been 55 shown but one embodiment of the invention which is now deemed preferable, but it is to be understood that changes and modifications may

be made within the scope of the appended claims without departing from the spirit of the invention.

Briefly and in its broadest aspect, the invention may include the following principal parts: First, 5 a central driving shaft having mounted thereon two similar flanges the surfaces of which are disposed in opposed relation to each other; second, a nut on the shaft engaging a threaded portion thereof so that the flanges may be adjusted toward and from each other; third, a thin cylindrical shell or tube disposed between the opposed flanges, the internal surface of this sleeve or tube 10 engaging narrow cylindrical ledges formed intermediate of the diameter of the flanges; fourth, 15 a heavy layer of rubber or other compressible and resilient material preferably molded to the outer surface of the shell or tube and having an outer cylindrical surface, the end walls of this compressible material being bevelled inwardly and 20 engaging corresponding bevelled portions of the flanges.

Referring more in detail to the figure of the drawing, I provide a driving shaft shown at 10 with a reduced end portion 11, the outer end of 25 this reduced portion being provided with screw threads 12. Engaging the screw threads is a nut 13, there also preferably being a washer 14 on the shaft 11 adjacent the nut.

Mounted upon the portion 11 of the driving 30 shaft 10 are flanges 15 similar to each other but disposed upon the driving shaft 10 in opposed relation to each other. These flanges have central openings so that they may freely pass over the reduced portion 11 of the driving shaft 10. 35 Intermediate their width there are provided narrow shelf-like cylindrical portions or ledges 16, and beyond this portion of each flange is an outwardly flared portion 17 as clearly indicated in the figure.

Centrally mounted upon and engaging the cylindrical ledges 16 of the flanges 15 is a cylindrical shell 18. This preferably is made of thin metal tubing closely fitting the diameter of the cylindrical portions of the flanges 16. Directly molded 45 to the outer surface of the shell or tubing 18 is a thick wall 19 of compressible and resilient material such as rubber. This may conveniently be directly molded to the shell or tubing 18, the shell being used directly in the mold within which the rubber is formed. The outer surface of this material is cylindrical and may be directly formed by means of the molding operation or may be subsequently surfaced as may be desired. Surrounding the outer surface of the compressible 50

and resilient material 19 is the abrasive or polishing band which may be of conventional form, that is it is preferably an endless band of flexible material such as fabric, the outer surface of which is charged with a suitable abrasive bonded in any preferred way to the surface of the fabric.

To mount the band in position upon the expandible wheel the nut 13 is adjusted so that the flanges 15 may be separated as far as possible and so that their flanged portions 17 may engage the outer or end walls of the material 19 without material pressure or compression. In this position of the flanges the band 20 is slipped over the outer surface of the material 19 and the nut 13 tightened upon the threaded portion 12 of the shaft portion 11. This adjustment of nut 13 forces the flanges 15 toward each other and permits the ends of shell 18 to slide along the cylindrical surfaces 16 of the flanges. Also it forces the flared portions 17 of the flanges tightly against the material 19 thus compressing this material laterally and forcing it slightly radially outward. This slight radial expansion of the material 19 serves to very tightly contact the outer periphery of the material 19 with the abrasive band 20 and serves to hold this band in driving relation to the wheel.

As the material 19 is mounted directly upon the shell or tube 18 and the tube rests upon cylindrical surfaces 16 concentric with the axis of rotation of the shaft 10, the assembled parts of the wheel will at all times remain in perfect central and balanced condition. It will further be noted that the flared portions 17 of the flanges 15 are widely spaced laterally and radially from the resilient material 19 adjacent the shell 18 so that when drawing the flanges together the material 19 adjacent the shell 18 will not be forced away from the ends of the shell 18.

I claim as my invention:

1. An expandible polishing wheel comprising in combination, a central cylindrical metal sleeve, compressible and resilient material surrounding the outer surface thereof, a flexible abrasive band surrounding said material, and oppositely disposed flanges engaging the end walls of said material and having narrow cylindrical surfaces thereon engaging and supporting the inner surface of said sleeve.

2. An expandible polishing wheel comprising in

combination, a central cylindrical metal sleeve, compressible and resilient material molded to and surrounding the outer surface thereof, a flexible abrasive band surrounding said material, and oppositely disposed flanges engaging and compressing the end walls of said material and having surfaces thereon on which the inner surface of said sleeve is centrally supported.

3. An expandible polishing wheel comprising in combination, a driving shaft, a centrally supported cylindrical metal sleeve, compressible and resilient material secured to and surrounding said sleeve, a flexible abrasive band surrounding said material, oppositely disposed flanges on said shaft adapted to engage and compress said material, cylindrical surfaces on said flanges intermediate their width centrally supporting said sleeve, and clamping means on said shaft for tightening said flanges upon said material whereby said band may be secured to and released from said material.

4. An expandible polishing wheel comprising in combination, a driving shaft, a centrally supported cylindrical metal sleeve, compressible and resilient material secured to and surrounding said sleeve, a flexible abrasive band surrounding said material, oppositely disposed flanges on said shaft adapted to engage and compress said material, cylindrical surfaces on said flanges intermediate their width centrally supporting said sleeve, outwardly flared portions on said flanges engaging the end walls of said material, and clamping means on said shaft for tightening said flanges upon said material whereby said band may be secured to and released from said material.

5. An expandible polishing wheel comprising in combination, a driving shaft, a centrally supported cylindrical metal sleeve, compressible and resilient material secured to and surrounding said sleeve having outwardly flared end surfaces, a flexible abrasive band surrounding said material, oppositely disposed flanges adapted to engage the outwardly flared end surfaces of and compress said material, cylindrical surfaces on said flanges centrally supporting said sleeve, and clamping means on said shaft for tightening said flanges upon said material whereby said band may be secured to and released from said material.

WILLIAM KRAUSE.
